UNITED STATES PATENT OFFICE

HARRY HALES ASBRIDGE, OF ASHTON-ON-MERSEY, ENGLAND, ASSIGNOR TO THE CHURCHILL MACHINE TOOL COMPANY LIMITED, OF BROADHEATH, NEAR MANCHESTER, ENGLAND, A BRITISH COMPANY

GRINDING OR ABRADING MACHINE

Application filed March 14, 1929, Serial No. 347,090, and in Great Britain April 24, 1928.

This invention relates to grinding or abrading machines, and has for its object the provision of improved mechanism for the feeding of the grinding wheel to the work piece, the feeding mechanism being of the type employing a face cam engaging a projection on the slide carrying the grinding wheel or disc, the cam being rotated by ratchet mechanism.

The invention, which is particularly applicable to machines for internal grinding operations, comprises the arrangement of the cam engaging the slide carrying the grinding wheel or disc and the operating ratchet of said cam, so that the feeding movement resulting from each cycle or revolution of the cam is made in separate and distinct stages, respectively adapted for a coarse or roughing feed and a fine or finishing feed.

Referring to the accompanying explanatory drawings:—

Figure 1 is a sectional elevation showing a sufficient portion of a grinding machine to illustrate the application of the invention.

Figure 2 is an end view showing the ratchet wheel and some associated parts of the feeding mechanism.

Figure 3 is a straight line development of the helical operating face of the cam.

Like reference letters in the different views 30 indicate like parts.

The slide *a* carrying grinding wheel *b* contacts through pin *c* with the cam *d*, the latter being a helical face cam and having intermittent rotary movements imparted thereto 35 through mechanism including a ratchet wheel *e*.

In accordance with this invention, the said face cam *d* is provided with a plurality of gaps or recesses (indicated at *d*¹ and *d*² in the 40 straight line development of the cam shown at Figure 3) into which the said pin *c* retreats (under the influence of the slide weight *f* or a spring) when each gap in its turn is brought into alignment with the pin on each revolution 45 of the cam. A plurality of gaps *e*¹ and *e*² are also provided in the periphery of the ratchet wheel *e*.

At the commencement of each forward or feed movement to be given to the slide *a* by the 50 cam *d* (against the action of the weight *f* or

an equivalent spring), the lower or inner end *A* of the cam spiral (see Figure 3) is in contact with the slide pin *c*. Under the slow intermittent movement of the cam imparted through the said ratchet wheel *e*, the position of contact of the cam with the pin progresses until the gap *d*¹ is brought into alignment with the pin *c* when the latter, under the influence of weight *f*, retreats into the said gap and the grinding wheel or disc is thus withdrawn from contact with the work piece in which it was operating. At the same time, the gap *e*¹ in the ratchet wheel *e* will have arrived in a position under the tip of the pawl *g* so that the latter will work idly in said gap and the intermittent rotary movement of the ratchet wheel is arrested.

The aforesaid stage of the feed movement provides for the coarse or rough grinding of the work piece and the automatic withdrawal of the grinding disc at the end of the stage interval can be utilized to true up the said disc or prepare it for the second or fine or finish grinding stage represented by the movement of the cam in contact with pin *c* progressing from the said gap *d*¹ to the gap *d*² which is deeper than *d*¹ and permits of a further retreat of the grinding disc to facilitate manipulation or removal of the work piece at the end of the grinding cycle represented by a complete revolution of the cam *d*.

To start the second stage grinding the ratchet wheel is given a small rotary movement by hand to carry the gap *e*¹ clear of the pawl *g*.

A screw and nut device as *h* and *i* or any equivalent and ordinary means are employed for the axial adjustment of the cam *d* to compensate for wear of the grinding disc and to suit the diameter thereof.

The circles shown in Figure 3 indicate the progressive positions of contact between the pin *c* of slide *a*, and the cam surface during a complete cycle or revolution of the cam.

What I claim is:—

1. In the feeding mechanism of grinding machines, in combination, a grinding wheel, a slide carrying said wheel, a bed upon which said slide is mounted, a spindle, a cam having a plurality of gaps or recesses in its operative

face keyed to said spindle, a ratchet wheel also secured upon said spindle with gaps therein corresponding with the gaps in the cam, a pawl imparting intermittent movements to said ratchet wheel and cam except when it enters the gaps in the ratchet wheel, and means upon said slide engaging said cam so that the slide has feed movements imparted to it by said cam.

10 2. In the feeding mechanism of grinding machines claimed in claim 1, means for traversing the cam axially along its spindle.

In testimony whereof I have signed my name to this specification.
